Primary Examiner — Maria J. Edwards(74) Attorney, Agent, or Firm — Legalforce RAPC Worldwide(57) CLAIM

The ornamental design for a video gaming glove, as shown and described.

DESCRIPTION

FIG. 1 is a front left side perspective view for a video gaming glove showing my new design, with the velcro strap in a closed position;

FIG. 2 is a front elevational view of FIG. 1 thereof;

FIG. 3 is a rear elevational view of FIG. 1 thereof; and,

FIG. 4 is a front left side perspective view of the video gaming glove of FIG. 1, with the velcro strap in an open position.

The broken lines depict environmental structure and form no part of the claimed design.
